UNITED STATES PATENT OFFICE

WILLIBALD HOFFMANN, OF MILWAUKEE, WISCONSIN

DISPLAY DEVICE FOR SHOW CASES, WINDOWS, AND SIMILAR PLACES

Application filed November 26, 1928. Serial No. 321,943.

This invention relates to display devices for show cases, windows, and similar places.

Objects of this invention are to provide a device which is adapted to display articles in a show case or window, which is constructed in the manner of a jointed rack, with the two parts pivotally joined therewith, one part adapted to be held at an angle to the horizontal, so that it will be displayed from the outer side of the window or show case, and with the other side displayed towards the inner side, and to provide means for holding the display rack in proper position, one of the portions of the rack being preferably made shorter than the other, whereby a greater angle may be imparted to one rack member than to the other.

Further objects are to provide a display rack which may be folded flat and shipped in a flat condition, which is so constructed that the marginal edge of the two racks at their point of union are reenforced so that distortion cannot occur although the racks may be made of relatively thin material.

Further objects are to provide a support for the two racks which may be adjusted so as to fit an inclination of the supporting surface, and in which this support reenforces one of the rack members, the reinforcing part for the other rack being so constructed that it is adapted to receive price tags or other devices of this nature.

An embodiment of the invention is shown in the accompanying drawings in which:

Figure 1 is a sectional elevation on the line 1—1 of Figure 2;

Figure 2 is a sectional view on the line 2—2 of Figure 1.

Referring to the drawings, it will be seen that the display rack comprises a front tray-like member 1 and a rear member 2. These members are preferably provided with marginal flanges 3, so that boxes, articles, or other members, as indicated at 4, may be displayed in the racks and may be arranged in any fanciful or attractive manner desired. These boxes, of course, are merely to indicate a displayed series of articles. Obviously, can goods, open packages of fruit, or

other articles, could be displayed in the same manner.

Preferably, the front tray is made shorter than the rear tray so that it may be supported at a greater angle than the rear tray, as shown in Figure 1. The front rack is displayed towards the outer face of the window or show case 5, so that it is freely visible to prospective patrons. The rear tray is displayed towards the rear of the show case or window so that this tray may be inspected by patrons within the store.

A pair of supporting arms or props 6 are provided and preferably formed from relatively heavy wire or rod. These arms are joined by a horizontal integral member 7, as shown in the drawings. The horizontal portion 7 is enclosed by a rolled flange or bead 8 formed integrally with the rear tray 2 and thus this transverse member 7 serves to reenforce the upper edge of the rear tray. The front tray has its upper edge reenforced by means of the upwardly turned flange 9 and it is to be noted that such flange may receive the clips for holding price tags or other placards, as indicated by the reference character 10.

It is preferable to provide elongated feet 11 which are pivotally joined to the bottom end of the rod 6, so that they may be turned, as shown in Figure 1, to support the device and to brace it, or may be turned, as shown in dotted lines in Figure 2. The purpose of having these feet pivoted is to permit the rod 6 to be folded flatly against one or the other of the trays, for instance the front tray, when the device is opened out flat for shipping. Obviously, the feet may be screw threaded upon the rods 6, if desired, without departing from the spirit of the invention.

The two trays are preferably joined by means of rivets or other suitable members 12 which pass through the marginal flanges 3.

It will be seen that a novel form of display rack has been provided which is of simple and substantial construction, which is properly braced, and which is so constructed that it is supported in its posi-

tion for display in a secure and substantial manner.

It is apparent that other forms of bracing or supporting means could be employed for holding the trays in their displayed position without departing from the scope of this invention.

It will be seen further that the display rack may be opened out flat and that the rods 6 may be folded flatly against the underside of one or the other of the trays, the feet 11 being turned at right angles to the position shown in Figure 1.

It is preferable to form these display racks of the same width as the window or show case with which they are used, although obviously they may be formed of other widths.

Although the invention has been described in considerable detail, such description is intended as illustrative rather than limiting as the invention may be variously embodied and as the scope of such invention is to be determined as claimed.

25 I claim:

1. A display rack for show cases, windows, and the like, said rack comprising a pair of trays having longitudinally extending marginal flanges hingedly joined adjacent the inner ends of said trays, said trays being adapted to be arranged at an angle to each other with their outer edges resting upon a supporting surface, and a pair of supporting legs pivotally joined to one of said trays adjacent their inner ends.

2. A display rack for show cases, windows, and the like, said rack comprising a pair of trays having longitudinally extending marginal flanges, said flanges being pivotally joined to thereby pivotally join said trays adjacent their inner ends, one of said trays having a transverse flange extending upwardly adjacent its inner end, the other of said trays having its body portion rolled to form a transverse bead, a transverse shaft positioned within said bead and having a pair of downwardly extending legs for supporting said trays with their inner ends elevated.

3. A display rack for show cases, windows, and the like, said rack comprising a pair of trays having longitudinally extending marginal flanges, said flanges being pivotally joined to thereby pivotally join said trays adjacent their inner ends, one of said trays having a transverse flange extending upwardly adjacent its inner end, the other of said trays having its body portion rolled to form a transverse bead, a transverse

40 shaft positioned within said bead and having a pair of downwardly extending legs for supporting said trays with their inner ends elevated, said legs having pivotally mounted feet elongated in one direction.

45 4. A display rack comprising a pair of

trays, said trays being pivotally joined adjacent their inner ends and adapted to be laid out flat for shipping, a rolled bead formed on the underside of one of said trays, a U-shaped supporting member having a pair of normally vertical legs and having an integral horizontal portion positioned within said bead, a pair of feet carried by said legs, said feet being elongated and being revoluble with reference to said legs, whereby said feet and said legs may be positioned closely adjacent the underside of one of said trays for shipping, and whereby said legs may extend downwardly and support the inner ends of said trays in an elevated position, one of said trays being shorter than the other.

In testimony that I claim the foregoing I have hereunto set my hand at Milwaukee, in the county of Milwaukee and State of Wisconsin.

WILLIBALD HOFFMANN.
